UNITED STATES PATENT OFFICE.

ALBERT LEGAULT, OF MONTREAL, QUEBEC, CANADA.

EMPLOYEE'S INDEXING SYSTEM.

1,244,061.

Specification of Letters Patent. Patented Oct. 23, 1917.

Application filed May 17, 1917. Serial No. 169,323.

To all whom it may concern:

Be it known that I, ALBERT LEGAULT, a subject of the King of Great Britain, residing at Montreal, Province of Quebec, Canada, have invented certain new and useful Improvements in Employees' Indexing Systems; and I do hereby declare that the following is a full, clear, and exact description of the invention, such as will enable others 5 skilled in the art to which it appertains to make and use the same.

The present invention relates to an indexing system and more particularly to a time recording apparatus to be used for recording 15 the employees often on duty of preferably a railroad company.

An object of the present invention is to provide an apparatus wherein the names of employees may be readily kept and classified, 20 and the names locked in such classified position to prevent their removal by unauthorized persons.

With the above and other objects in view which will hereinafter appear as the description continues, the invention consists of the 25 novel features of construction, combination and formation of parts as will be herein-after more fully described and particularly pointed out in the appended claims.

30 In the accompanying drawings has been shown the simple and preferred form of the invention, it being, however, understood that no limitation is necessarily made to the precise structural details herein exhibited, but 35 the right is hereby reserved to any changes, alterations or modifications to which recourse may be had that come within the scope of the claims without departing from the spirit of the invention or sacrificing the 40 efficiency of the same.

In the accompanying drawings:

Figure 1 is a front elevation of the apparatus embodying the present invention;

Fig. 2 is a side elevation of the same with 45 the door removed;

Fig. 3 is a vertical cross section;

Fig. 4 is a detail enlarged elevation;

Fig. 5 is an enlarged detail section;

Fig. 6 is an enlarged detail horizontal 50 section;

Fig. 7 is an enlarged detail sectional view through one of the endless belts and operating means;

Fig. 8 is a detail sectional view through 55 one of the adjustable bearings;

Fig. 9 is an enlarged detail side elevation; Fig. 10 is a plan view of one of the name recording blocks, and

Fig. 11 is an enlarged detail elevation.

Referring now more particularly to the 60 accompanying drawings wherein like and corresponding parts are designated by similar reference characters throughout the several views.

The cabinet herein shown for retaining 65 the apparatus forming the subject matter of the present invention comprises a rear wall 1, side walls 2 and a top and bottom indicated by the numerals 3 and 4 respectively. The front of the cabinet is inclosed by means 70 of the glass plate 5 which is retained in position by means of the strips 6 secured to the side walls and bottom of the cabinet and the latch member 7 locks the plate within the strip 6, but permits its ready removal when 75 it is desired to clean the same. The side walls 2 of the cabinet are provided with the elongated openings 8, whereby access may be gained to the interior of the cabinet and these openings are to be closed by means of 80 the doors 9 which may be provided with a padlock for locking the same closed. Arranged in front of the cabinet and behind the plate glass 5 is a frame 10 which is divided up in to a plurality of sections and 85 each section being designated as shown in Fig. 1, according to the position held by the employees and their present location. Extending through the top 3 of the cabinet and resting within the upper end of the frame 10 90 are the plates 11 which plates contain a list of employees' names and the date on which they entered into employment of the company. These two lists are designated by the words "Engineers" and "Firemen" (sen- 95 iority list). In other words, in this list is contained the names of employees who have been with the company a long period of time and who have preference to different work over other employees. The remaining sec- 100 tions of this partition 10 are divided up into slots in which are adapted to be retained the name recording blocks 12 and these blocks 12 are adapted to be locked within the recesses. These name recording blocks 12 comprise an 105 elongated rectangular strip of material having the name of one employee on the face thereof and the opposite face of these blocks 12 are provided each with a recess 13. Carried by the inner face of the partition 10 are 110

a plurality of spring actuated pawls 14 and the free ends of these pawls are adapted to rest within the recesses 13 within the blocks 12 for retaining these blocks in locked position within the partition 10 and by so locking these blocks within the partition 10 they can not be removed without first unlocking the door 9 and grasping the pawls 14, by running the hand through the opening 8 within either side of the cabinet. Arranged 10 within the cabinet is a central partition 15 and to each side of this partition 15 are secured the brackets 16. These brackets each carry a pair of spaced bearing arms 17 in 15 which are journaled the shafts 18 and adapted to rest against these shafts 18 are the set screws 19, the purpose of which will be later described. Carried by the lower shaft 18 is a pair of idler wheels 20 and carried by the 20 upper shaft 18 are a pair of gear wheels 21. Extending over these wheels 20 and 21 is an endless belt comprising a plurality of transversely extending bars 22 which are flexibly connected by means of the hinged plates 23. 25 The inner walls of each of these blocks 22 are provided with a spring actuated pawl 14 and the outer walls of these blocks 22 are provided with the recesses 24 for the reception of the name recording blocks 12. These blocks 22 are also provided on their inner face with gear teeth 25 which mesh with the teeth of the gears 21, so that when the gears 21 are rotated the endless belt will move. Carried by the upper shaft 18 is a hand 30 wheel 26, whereby the gear wheels 21 may be manually rotated. The set screws 19 provide means for holding the shafts 18 to and from each other so that any slack within this endless belt may be readily taken up. The 35 side walls 2 of the cabinet are provided with projecting portions 27 which are adapted to register with the sides of the partition 10 and these projecting portions 27 are provided with the openings 28 which are adapted 40 to register with the recesses formed within the partition 10 and the recesses 24 formed in the partition 10 and the recesses 24 formed within the endless conveyers, so that the name recording blocks may be inserted through the openings formed within these extensions 45 27 and placed within the recess formed within the blocks 22 and the partition 10. The 50 openings 29 within the extensions 27 which register with the recesses 24 are of such a length as to only permit the entrance of six of the blocks 12 and therefore only six of these blocks are to be retained within each 55 endless belt at one time. Arranged upon the outer face of the partition 10 are the numbers 1 to 6 inclusive which are adapted to 60 register with the recesses 24 in the endless belts, so that the employee who is to be next called for duty may place his block 12 through the opening 29 into one of the recesses 24 which correspond with the numeral 65 one in the partition 10; this indicating that

the employee is the first one to be called for duty. The next employees in line to be called for duty will likewise place their blocks 12 within the recesses 24 until six in number have been retained in each endless 70 belt. The outer end of each block projects beneath the extensions 27 as better shown in Fig. 6 of the drawings, thereby providing a locking means to prevent the rotation of the endless belt until the block corresponding 75 with the numeral one has been removed. The employee, whose name appears on the block corresponding with the numeral one, will, when called to duty, request that his block be removed by releasing the pawl 14, 80 which is holding the same in locked position. In so removing this block the endless belt may then be turned and the next succeeding block will register with the numeral one and indicate that the employee, whose name appears on this block, is the next to be called. When an employee has been called to duty, the block with his name thereon is removed from the endless belt and placed within one of the recesses formed within the partition 90 10 under the title of "Men on duty." If the employee is not on duty his block will then be properly classified under the titles of "Sick list" or "Men on leave." Arranged within the lower end of the casing are the 95 compartments 30 which may contain unused blocks.

In Fig. 1 of the drawings, it will be noted that the partition 10 is divided up into sections and each section being classified and titled with a name as to the position of the employee, but, of course, it is to be understood that this partition may be sub-divided and re-classified into any number of sections desired, according to the position and number of employees and the specific manner of classifying these names may be arranged in accordance with the desire of the operator.

Having thus fully described my invention, what I claim as new and desire to secure by 110 Letters Patent is:

1. In a device of the character described the combination of a cabinet, of a partition arranged within said cabinet, the outer face of said partition having a plurality of recesses formed therein, blocks adapted to rest within said recesses and projecting beyond said casing, and spring actuated pawls secured to the rear face of said partition, substantially as and for the purpose specified. 115

2. In a device of the character described comprising a cabinet, a plurality of endless belts mounted within said cabinet, means for moving said belts, each of said belts having a plurality of recesses formed within the outer faces thereof, blocks adapted to be retained within said recesses, and said blocks adapted to lock said belts against movement substantially as and for the purpose set forth. 125

3. In a device of the character described comprising a cabinet, a plurality of endless belts arranged within said cabinet, each of said endless belts comprising a plurality of hingedly connected bars, the outer face of each of said bars having recesses formed therein, blocks adapted to be placed within said recesses, and spring actuated pawls carried by the inner face of each of said bars for engaging said blocks substantially as and for the purpose specified.

In witness whereof I have hereunto set my hand.

ALBERT LEGAULT.

Copies of this patent may be obtained for five cents each, by addressing the "Commissioner of Patents, Washington, D. C."
